COMBINED TIMER AND SELECTOR SWITCH MECHANISM

Wallace F. Oliver, South Bend, Ind., assignor to
 Bendix Home Appliances, Inc., South Bend,
 Ind., a corporation of Delaware

Application September 25, 1942, Serial No. 459,668

3 Claims. (Cl. 200—33)

1

This invention relates to a combined timer and selector switch mechanism particularly adapted for control of the operation of automatic washing machines.

In accordance with prior practice it has been necessary to include two separate switches, one a timer and one separate switch which has been used for selecting a water temperature corresponding to the character of the washing operation, for instance, lukewarm water for woolens or silks and a hotter wash water temperature for normal loads of cotton material. It has frequently happened that an operator having set the switch for cotton goods calling for extremely hot water may have neglected re-setting the selector switch to warm water position for the washing of woolens and the result may have been the ruining of material because of the use of excessively hot water.

The object of this invention is to provide a combined timer mechanism and selector switch mechanism which can be used to control an automatic washing machine and being so arranged that the selector switch will be automatically returned to a normal position at the end of each washing operation and require a setting by the operator before a new washing operation can be performed thereby eliminating the possibility of damage from failure to consider the resetting of the mechanism.

In carrying out my invention I incorporate the selector switch and the timer switch within the same housing and so associate the two switch mechanisms that the selector switch mechanism is returned to its off position at the end of each washing operation. In accordance with one modification the parts are all so coordinated that the only setting required by the operator to initiate the washing operation is the actuation of the selector switch.

In accordance with my present invention the selector switch may be operated to start the timer motor and if desired the main motor of the washing machine which may be connected with the timer and the selector switch will also automatically be disconnected by the timer mechanism at the end of the timer cycle.

The two embodiments of my invention are illustrated in the accompanying drawings in which,

Fig. 1 is a plan of the combined timer and selector switch mechanisms, partly in section.

Fig. 2 is a section on the line 2—2 of Fig. 1.

Fig. 3 is a section on the line 3—3 of Fig. 1.

Fig. 4 is a section on the line 4—4 of Fig. 1.

2

Fig. 5 is a section on the line 5—5 of Fig. 1.

Fig. 6 is a section on the line 6—6 of Fig. 1.

Fig. 7 is a section on the line 7—7 of Fig. 1 and illustrates the preferred embodiment of the invention.

Fig. 8 is an elevation of the dials for manually rotating either the selector switch shaft or the timer switch shaft.

Fig. 9 is a section on the line 9—9 of Fig. 1 illustrating a modification of my invention.

Fig. 10 is a view similar to Fig. 1 but including a wiring diagram and showing the parts in a position corresponding to a position "B" of the selector dial.

Fig. 11 is a view similar to Fig. 10 but showing the parts in position and after the selector dial has been moved to a position "C".

Since the motor mechanism for driving the timer shaft forms no part of the present invention it has not been herein illustrated in detail. It is preferably of the type which rotates the timer shaft with a step by step quick motion, each movement being followed by a period of rest of short duration, say one minute or less. Several different mechanisms have been patented for accomplishing such a step by step movement, one such mechanism being illustrated in United States Patent to Ray W. Scott and Andrew O. McCollum, No. 2,187,795 of January 23, 1940.

Referring to Fig. 1, the timer motor and gear housing 10 contain motor and gear mechanism not shown for driving the shaft 11 in a clockwise direction when facing the left end of Fig. 1. Within the housing 10, but not illustrated in the

drawing, is a ratchet mechanism which permits the shaft 11 to be rotated manually in a clockwise direction but which prevents a manual counter-clockwise rotation of the shaft 11. A plurality of cams 13, 14, 15, 16 and 17 of insulating

material are mounted along the shaft 11 spaced from one another by bushings 20 and caused to rotate with the shaft 11 by mating flat surfaces 21 and 22 of the shaft and cams. The external contours of cams 13 and 15 are shown respectively in Figs. 3 and 4. The external contours of the cams 14, 16 and 17 are not illustrated, though their functions will be explained hereafter as a part of the description of operation. A circular timer dial 25 is mounted on the left end of the

shaft 11 and is provided with a pawl 26, Fig. 6, pressed by a spring 27 so as to engage the shoulder 28 in shaft 11 to drive the shaft 11 when the dial is rotated by hand in a clockwise direction, but to slip out of the depression in the shaft 11 when the dial is rotated by hand in a counter-

clockwise direction, thus preventing strain being placed upon the ratchet mechanism which prevents the counter-clockwise rotation of shaft 11.

A sleeve 30 surrounds and is journaled upon a portion of shaft 11 and carries at its right end, Fig. 1, a cam 31 of insulating material formed generally similarly to cams 13, 14, 15, 16 and 17. The actual contour of cam 31 is shown in Fig. 2. The sleeve 30 also carries a metal cam 33 illustrated in Figs. 1, 7 and 9 having three depressions 34 located at positions A, B and C for engagement with the end 35 of a plunger 36 spring pressed to the left, Fig. 1, by a spring 38 seated in a hollow portion of the plunger 36. The plunger 36 carries a contact blade 40, Fig. 1, the function of which will be described later. As the plunger 36 moves to the left to position B on the cam 33 the blade 40 completes an electrical connection between springs 41 and 42 and as the plunger 36 moves into position C on the cam 33 the blade 40 completes connection between the springs 42 and 44 and severs the connection between springs 41 and 42. A selector dial 46, Figs. 1 and 8, is fixed to the left end of the sleeve 30, Fig. 1, for manually rotating the sleeve 30 through an arc of substantially 60°, its normal position being shown in Fig. 8. When the sleeve 30 is manually rotated in a counter-clockwise direction, the depressed portion of the cam 31, Fig. 2, permits the contact spring 48 to move under its own spring tension for closing the circuit between contacts 49 and 50. The contact 50 is electrically connected with the metallic bus bar 51 insulatedly mounted on the arm 53 which forms one bearing for the slidable plunger 36. The sleeve 30 is provided with a plunger 56 pressed by spring 57 into a notch 58, Fig. 7, in the shaft 11. The resistance of the plunger 56 to dislodgment from the notch 58 in shaft 11 is greater than the resistance of the end 35 of the plunger 36 to dislodgment from the depressions 34 at the points A, B and C in the cam 33.

In accordance with the modification shown in Fig. 9 the shaft 11 is provided with an additional notch 59 similar to the notch 58 of Fig. 7. The resistance of the plunger 56 to dislodgment from the notch 59 is greater than the resistance of the end 35 of plunger 36 to dislodgment from the depressions 34 in the cam 33. Therefore clockwise rotation of shaft 11 when the plunger 56 is in either notch 58 or notch 59 will cause the sleeve 30 and its carried parts to rotate with the shaft 11.

The operation of my combined selector switch and timer can best be understood by considering its operation when connected to actuate an automatic washing machine circuit such as shown in Figures 10 and 11. Such an operation is as follows.

The conductor 60 from the live side of a source of current marked "Line" is connected to the contact spring 48 normally disconnected from the bus bar 51 by open contacts 49 and 50.

The operator wishing to start the washing machine on its cycle rotates the selector dial 46, Fig. 8, in a counter-clockwise direction until the words "mix or soak" come within the hollow part of the pointer. This movement of the dial 46 rotates the cam 31 closing contacts 49 and 50 connecting the live side of the current source to the bus bar 51. In accordance with the preferred embodiment of my invention as illustrated in Fig. 7 and the solid lines of Figs. 10 and 11 the main motor circuit remains open at contacts 63 and 64. So that in order that the circuit of the

main motor 65 and the timer motor 66 may be closed the timer dial 25 must be rotated in a clockwise direction, there being a depression of the proper circumferential length for the entire "soak" period in the external surface of cam 17 which controls contacts 63 and 64. When both the selector dial 46 and the timer dial 25 thus have been manually moved from their normal positions, the main motor 65 and the timer motor 66 are simultaneously started. The circuits for the timer motor 66 and the main motor 65 being through conductors 70 to the grounded side 71 of the source of current.

Inasmuch as the selector dial has now been turned to the position marked "mix or soak," the cam 33 has been moved to its C position and the plunger 36 has been moved to the left to a position in which the blade 40 completes connection between the springs 42 and 44 as shown in Fig. 11. The cam 13, Fig. 3, is so shaped that the contacts 45 and 47 are closed throughout the entire "soak" period. This brings about the completion of the circuit through the mix inlet valve solenoid 77 from bus bar 51 through the now closed contacts 45 and 47, conductor 76, float switch contacts 78 and 79 and conductor 71 to the grounded side of the source. The energization of solenoid 77 opens the mix water valve permits lukewarm water to enter the washing chamber of the washing machine. The water continues to flow into the washing chamber of the washing machine until the float switch contacts 78 and 79 are opened by the operation of a float not shown. The timer motor and the main motor continue to operate for agitating the clothes in the lukewarm soak water until the timer motor 66 has rotated the shaft 11 and its associated cams through such an arc that the first depression in cam 17 is passed and the associated contacts 63 and 64 are opened. As shown in Fig. 8, this requires a rotation of the shaft 11 and the dial 25 through substantially fifty degrees, the dial 25 now having been rotated in a clockwise direction until the second off position stands under the pointer. Just before the timer dial has arrived at its second off position the cam 15 will have arrived at a position in which a short depression in its surface permits the closure of contacts 81 and 82 for closing a circuit from the bus bar 51 through conductor 83 and drain solenoid 84 to conductor 71 and the ground side of the current source. This opens the drain valve and causes the removal of water from the washing chamber of the machine.

When the operator of the washing machine considers that the wet clothes have soaked sufficiently long in the washing machine she rotates the timer dial 25 through a very short arc in the clockwise direction causing a second depression in the cam 17 to permit a second closing of the contacts 63 and 64 and a second starting of the main motor 65 and timer motor 66. If now the operator desires to wash delicate fabrics which require lukewarm water, she does not reset the selector switch but allows it to remain in the C or "mix" position. When the shaft 11 has been rotated in a clockwise direction either manually or by the now running timer motor to a position which brings the depression in cam 14 to the proper position for closing contacts 73 and 74, Fig. 11, current flows from the bus bar 51 through the spring 42, blade 40, spring 44, conductor 76, mix water valve solenoid 77, now closed contacts 78 and 79 of the float switch to conductor 71 connected to the ground side of

the source. This causes the washing operation to proceed in mixed or lukewarm water. For a hot water wash she rotates the selector dial 46 in a clockwise direction until the word "hot" comes within the hollow part of the pointer, Fig. 8. This moves the cam 33 until the plunger 36 rests in the depression B and causes the blade 40 to complete connection between the springs 41 and 42 as shown in Fig. 10.

The valves controlled by the "mix" and "hot" solenoids may be of the general type shown in Patent 2,269,259, and the thermostatically controlled mixing valve supplying mixed water may be of the type shown in Patent 2,310,975.

From this point in the cycle of the operations, the timer motor continues the clockwise rotation of the shaft 11 and its associated cams causing the properly timed operation of the mixed water inlet as controlled by the contour of the cam 13, the hot water inlet as controlled by the contour of cam 14, the drain solenoid as controlled by the contour of the cam 15, the various speed changes from low speed washing to high speed extracting and back to rinsing and again to extracting and finally to tumbling as controlled by the shifter solenoid 90 and contacts 91 and 92 and cam 16 until the plunger 56 drops into the notch 58, Fig. 7. When this happens the cam 33 which as just described was set in position B, or "hot" position is picked up and moved in a clockwise direction back to its normal or A position. As heretofore stated, the shaft 11 moves step by step throughout the entire cycle. The last step rotates the cam 31 on the sleeve 30 and the cam 17 carried on the shaft 11 to their normal positions in which the connection between the live side of the source and bus bar 51 is interrupted at contacts 49 and 50 and in which the circuits of the main and timer motors are also interrupted at contacts 63 and 64 controlled by cam 17. All the parts thus having been returned to their normal positions, the selector switch is in its off position and the washing machine cannot be again started for another operation unless the selector switch is manually moved in a counter-clockwise direction to complete the circuit from the live side of the source to bus bar 51.

If the operator does not move the selector dial away from the "mix and soak" position at the end of the "soak" period, then no current can pass through the hot inlet valve solenoid because its circuit will be permanently broken by reason of the blade 40 having been moved to a position opening the circuit between springs 41 and 42. During the washing operation contacts 13 and 14 are opened and closed by cam 14 in exactly the same manner as when the machine was operated for a cotton wash, but under these conditions whenever contacts 13 and 14 are closed by cam 14 warm water instead of hot water is admitted to the washing chamber.

In accordance with the modification of Fig. 9, the starting and stopping of the main and timer motors are entirely under the control of contacts 49 and 50 of cam 31 mounted upon sleeve 30 to which the selector dial 46 is attached. When this modification is incorporated in my invention the operator rotates the selector dial in a counter-clockwise direction until the words "mix or soak" appear within the hollow part of the pointer. In this position the plunger 56, Fig. 9, drops in to the notch 59 in shaft 11, the main motor 65 and the timer motor 66 having been started by current flowing from the live side of the source of

current through conductor 60, contact spring 48, contacts 49 and 50, bus bar 51, the dotted conductor 94 and conductor 70, through the coils of main motor 65 and timer motor 66 to the grounded conductor 71 of the source of current. The solid conductor 85, Figs. 10 and 11, and the cam 17 and its associated contact springs may be omitted in accordance with the present modification as they will perform no operative function. The clockwise rotation of the shaft 11 now carries the plunger 56, the sleeve 30, cams 33 and 31 and selector dial 46 in the clockwise direction of rotation until the dial 46 and its associated cams 31 and 33 have been moved back to their normal positions. When the cam 31 returns to its normal position, Fig. 2, contacts 49 and 50 are opened and the washing machine is thus brought to rest at the end of the "soak" period. The operator returning to the machine starts it on its washing operation by merely moving the selector dial either to the "mix or soak" position or the "hot" position, depending upon whether she is expecting to wash woolens, silks, or linens, or is expecting to wash cottons. All of the operations of the washing machine now proceed through the controls of cams 13, 14, 15 and 16 in exactly the same manner as was described in connection with the preferred embodiment of this invention. However, at the end of the cycle of operations the circuits of the main motor 65 and the timer motor 66 are interrupted only at contacts 49 and 50 controlled by cam 31, the plunger 56 having dropped into the notch 58 upon the arrival of that notch under the plunger 56 and the parts movable with the plunger 56 having been moved along with the shaft 11 back to normal position.

The type of washing machine to which my invention has been applied is illustrated in United States patent to J. W. Chamberlin and R. E. Bassett, Jr., Number 2,165,884, of July 11, 1939.

It is understood that the timer and selector switch mechanism has been illustrated as applied to a specific type of automatic washing machine for purposes of illustration and that various modifications in this application may be made.

What I claim is:

1. In a combined selector and timer mechanism, a timer shaft, a timer motor for driving the timer shaft, a plurality of pairs of contacts sequentially operated by the rotation of the timer shaft, a timer dial for manually rotating the timer shaft in advance of the position to which it has been rotated by the timer motor and for indicating its displacement from normal, a selector dial co-axial with the timer dial and having its shaft co-axial with the timer shaft, a plurality of pairs of contacts operated by the rotation of the selector shaft, one pair of selector controlled contacts being in the electric circuit of the timer motor and all of the contacts controlled thereby, a second pair of selector controlled contacts, and a third pair of selector controlled contacts, and a connection between the timer shaft and the selector shaft for rotating the selector shaft with the timer shaft to force the selector shaft, its associated dial and contacts to their normal position as and when the timer shaft and its associated dial and contacts are returned to their normal position.

2. In a combined selector and timer mechanism, a timer shaft, a timer motor for driving the timer shaft, a plurality of pairs of contacts sequentially operated by the rotation of the timer shaft, a timer dial for manually rotating the

timer shaft in advance of the position to which it has been rotated by the timer motor and for indicating its displacement from normal, a selector dial co-axial with the timer dial and having its shaft co-axial with the timer shaft, a plurality of pairs of contacts selectively operated by the rotation of the selector shaft, and a connection between the timer shaft and the selector shaft for rotating the selector shaft with the timer shaft to force the selector shaft and its associated dial and contacts to their normal position as and when the timer shaft and its associated dial and contacts are returned to their normal position.

3. In a combined selector and timer mechanism of the character described, a timer shaft, a timer dial, a selector dial co-axial with the timer dial and a selector shaft co-axial with the timer shaft, a plurality of pairs of contacts selectively operated by the rotation of the selector shaft, and a connection between the timer shaft and the selector shaft for rotating the selector shaft with

the timer shaft to force the selector shaft and its associated dial and contacts to their normal position as and when the timer shaft is returned to normal position.
